(57) **CLAIM**

The ornamental design for a capsule, as shown and described.

DESCRIPTION

FIG. 1 is a top perspective view of a capsule showing my new design;

FIG. 2 is another perspective view thereof, showing the top cover partially removed wherein the intersecting diagonal lines represent a filter;

FIG. 3 is a bottom perspective view thereof;

FIG. 4 is a front view thereof;

FIG. 5 is a left side view thereof, the right side view being a mirror image thereof;

FIG. 6 is a rear view thereof;

FIG. 7 is a top view thereof;

FIG. 8 is a bottom view thereof;

FIG. 9 is a top perspective view of a second embodiment thereof;

FIG. 10 is another perspective view thereof, showing the top cover partially removed wherein the intersecting diagonal lines represent a filter;

FIG. 11 is a bottom perspective view thereof;

FIG. 12 is a front view thereof;

FIG. 13 is a left side view thereof, the right side view being a mirror image thereof;

FIG. 14 is a rear view thereof;

FIG. 15 is a top view thereof;

FIG. 16 is a bottom view thereof;

FIG. 17 is a top perspective view of a third embodiment thereof;

FIG. 18 is another perspective view thereof, showing the top cover partially removed wherein the intersecting diagonal lines represent a filter;

FIG. 19 is a bottom perspective view thereof;

FIG. 20 is a front view thereof;

FIG. 21 is a left side view thereof, the right side view being a mirror image thereof;

FIG. 22 is a rear view thereof;

FIG. 23 is a top view thereof; and,

FIG. 24 is a bottom view thereof.

The broken lines in the drawings represent structure and features of the capsule which form no part of the claimed design. The two closely placed vertical broken lines centered on the front surface of the capsule are unclaimed lines on a claimed surface. The groups of parallel diagonal lines in the second embodiment represent transparency.
